UNITED STATES PATENT OFFICE.

KARL MAYBACH, OF FRIEDRICHSHAFEN-ON-THE-BODENSEE, GERMANY, ASSIGNOR
TO THE FIRM: MAYBACH MOTORENBAU-GESELLSCHAFT MIT BESCHRÄNKTER HAF-
TUNG, OF FRIEDRICHSHAFEN-ON-THE-BODENSEE, GERMANY.

INTERNAL-COMBUSTION ENGINE.

Application filed May 5, 1921. Serial No. 467,193.

To all whom it may concern:

Be it known that I, KARL MAYBACH, a citizen of the German Empire, residing at Friedrichshafen-on-the-Bodensee, Germany, 5 have invented certain new and useful Improvements in Internal-Combustion Engines, of which the following is a specification.

My invention refers to internal combustion engines and more especially to the way in which the cylinders are arranged and connected with the engine casing.

As is well known, the cylinders of internal combustion engines are as a rule arranged on the crank-casing, being fastened to the said casing by means of flanges provided on the lower halves of the cylinders which latter thus project above the casing by the greater part of their length. This 15 construction is disadvantageous inasmuch as it results in a comparatively low casing of but very inferior stiffness, more especially in the case of multi-cylinder engines. These disadvantages are particularly noticeable in the case of cast aluminum casings. Furthermore the flanges on the cylinders are not easily accessible and show a tendency to break, even if made very strong. It has been endeavoured lately to accommodate 20 the whole of the valve control within the casing in order to obviate the above disadvantages and to obtain a better silencing effect, besides improving lubrication. In some foreign types of motors attempts have 25 been made in this direction by subdividing the cylinder into a body portion and a head portion, the casing then enclosing the body including the cooling water jacket, while the head is fitted on the casing and the body 30 separately, the engine thus obtained presenting a very plain and even outward appearance. However, this construction involves grave disadvantages inasmuch as it is very difficult to tighten such large surfaces in a reliable manner so as to render 35 them leak-proof against the pressure exerted by the combustion gases and the cooling water.

In order to avoid these drawbacks, I arrange 40 each cylinder, which is made in one piece, substantially within the casing which is elongated upwards to a corresponding extent, practically only that part of the cylinder, which contains the valve cham-

bers, projecting from the casing, whereby 55 the cylinders are supported in a very stable manner. The valve control is placed within the crank casing so that the engine presents a very smooth outer appearance. Both 60 silencing and lubrication are greatly improved, while the valve gear can be made easily accessible by means of suitable openings in the casing wall.

In the drawings affixed to this specification and forming part thereof, a four-cylinder engine embodying my invention is illustrated diagrammatically by way of example.

In the drawings Fig. 1 is a cross-section, partly in elevation, and Fig. 2 is a longitudinal section, with part of the cylinder shown in side view.

The four cylinders are arranged in pairs, each pair forming a single casting comprising the bodies A^1 , A^2 , A^3 , A^4 and the heads B^1 , B^2 , B^3 , B^4 of the pairs. The overall height of each cylinder is equal to the height of the body plus the height of the head. The bodies including the cooling water jackets a are enclosed entirely within the 75 casing D , while the heads C are arranged outside and are supported by the surface b^1 of the upper portion of the casing. The cylinders are fixed in position by means of bolts H disposed between the two cylinder 80 castings and at each end, respectively. These bolts press the cylinders with their heads against the surface b^1 of the casing D . The lower ends of the bolts are held in position by the caps J of the bearings. In 85 the plane of the upper rim of the casing the bolts are provided as usual with flanges H^1 allowing the crank shaft G to be placed in the bearings independently of the cylinders which are fitted in later on. Removing the 90 cylinders for the purpose of overhauling them is now effected simply by loosening the nuts at the cylinder heads, the bolts themselves still holding together the crank shaft 95 bearings and in the casing D are openings L closed up with lids M and rendering the valve gear easily accessible. E and F are a 100 cover and an oil sump, respectively.

I wish it to be understood that I do not desire to be limited to the exact details of construction shown and described, for many 105 obvious modifications will readily occur to a person skilled in the art.

I claim:

1. In an internal combustion engine in combination a crank case and a cylinder and cylinder head cast in one piece and freely suspended from the upper edge of said crank case with the head only projecting above the case.
  2. In an internal combustion engine, a crank case, a cylinder and cylinder head having laterally extending supporting surfaces about the head seating upon the upper edge of the crank case whereby to freely suspend the cylinder within said case from said supporting surfaces.
  3. In an internal combustion engine, a crank case, a cylinder block having an external supporting flange projecting therewith from about its upper portion and seating upon the upper edge of the crank case, thereby suspending said cylinder from said edge within the case.
  4. In an internal combustion engine, a crank case, a cylinder block including a cylinder head, said head projecting beyond the side walls of the cylinder to form a support for seating upon the upper edge of the crank case and suspending the cylinder
- within said case in spaced relation thereto, a crank shaft bearing at the lower portion of the crank case, and securing means intermediate the block and shaft bearing.
5. In an internal combustion engine, a crank case, a crank shaft bearing at the base thereof, a cylinder block including an integral cylinder head having supporting means projecting therefrom from which the cylinder is freely suspended within the case, and tension means passing through the block and shaft bearing for holding the block onto the casing.
6. In an internal combustion engine, a crank case, a crank shaft bearing at the base thereof, a bearing cap therefor, a cylinder block including a cylinder and head in one piece having supporting means about the upper end of the block for sustaining the block upon the upper edge of the crank case, tension rods passing through the cylinder head, the shaft bearing and cap, and closure means for the base of the crank case.

In testimony whereof I affix my signature.

KARL MAYBACH.
